UNITED STATES PATENT OFFICE.

HENRY BREHMER, OF STAPLETON, ASSIGNOR TO DAVID WOLFE BRUCE, OF NEW YORK, N. Y.

DESIGN FOR TYPE.

SPECIFICATION forming part of Design No. 16,600, dated April 6, 1886.

Application filed March 4, 1886. Serial No. 194,070. Term of patent 14 years.

To all whom it may concern:

Be it known that I, HENRY BREHMER, (assignor to DAVID WOLFE BRUCE,) of Stapleton, Richmond county, New York, have invented and originated a new Design for a Font of Printing - Type, of which the following is a specification.

The nature of my design is clearly shown in the accompanying typographic impression, to which reference is made; and it consists of an ornamental letter shaded upon the right and below by a lighter line. The lower portion of the letter is formed heavier than its upper portion. The upper portions of the A, H, I, J, K, L, M, N, U, V, W, X, and Y are crossed by the short horizontal lines, as shown. The central ornament of the A and H consists of the wedge-shaped figure, the upper portion of which is concaved.

10 The character of the design is preserved in the symbol &, the punctuation - marks, the numerals, and the dollar and pound-sterling marks.

What I claim as new is—

The design for a font of printing-type, as shown, the same consisting of an ornamental letter made heavier at its lower portion than at its upper portion, shaded upon the right and below by a lighter line, the upper portions of the A, H, I, J, K, L, M, N, U, V, W, 30 X, and Y crossed by the light horizontal lines, as shown, the central ornament of the A and H consisting of the wedge-shaped figure, the upper portion of which is concaved, and the character of the design preserved in the symbol &, the punctuation-marks, numerals, and dollar and pound-sterling marks.

HENRY BREHMER.
